AUTOMOBILE CURTAIN WINDOW

Original Filed Aug. 22, 1922

Inventor
William M. Cloninger

By

John S. Dugger
Attorney

UNITED STATES PATENT OFFICE.

WILLIAM M. CLONINGER, OF MUSKOGEE, OKLAHOMA.

AUTOMOBILE CURTAIN WINDOW.

Application filed August 22, 1922, Serial No. 583,641. Renewed March 19, 1924.

To all whom it may concern:

Be it known that I, WILLIAM M. CLONINGER, a citizen of the United States, residing at Muskogee, in the county of Muskogee and

5 State of Oklahoma, have invented certain new and useful Improvements in Automobile Curtain Windows, of which the following is a specification.

This invention relates to new and useful 10 improvements in automobile curtain windows.

One object of my invention is to provide a construction in which the window pane and edges of the window pane opening of the curtain material will be securely 15 held in place between the members of the window frame without stitching.

A further object of my invention is to provide an automobile curtain window which 20 will be simple and economical in construction and may be very easily and quickly applied.

A still further object of my invention is 25 to provide a construction which will permit an old or broken window pane to be quickly removed and replaced by a new window.

With the foregoing and other objects in view that will appear as the nature of the invention is better understood, the same consists 30 in the novel features of construction, combination and arrangement of parts illustrated in the drawings and more particularly pointed out in the appended claim.

In the accompanying drawings, which are 35 for illustrative purposes only and are therefore not drawn to scale:—

Figure 1 is a front elevation of the automobile curtain window.

Figure 2 is a plan view of one of the 40 frame members of the window.

Figure 3 is a longitudinal sectional view of the window cut on the line 3—3 of Figure 1.

Figure 4 is a transverse sectional view 45 of the window cut on the line 4—4 of Figure 1.

Figure 5 is a transverse sectional view of the window cut on the line 5—5 of Figure 1.

50 Referring to the drawings for a more particular description of my invention and in which drawings like parts are designated by like reference characters throughout the several views, my invention comprises a pair of outer and inner elongated metal frames 1 and 2 of general rectangular outline, be-

tween which the window pane 3 and edge, as 4, of the window curtain opening are held, as will presently appear.

The outer frame 1 is preferably of concave-convex form in cross section and is provided at suitable spaced intervals along its edge or margin with the lugs 5 adapted to pass through corresponding transverse openings 6 formed in the inner frame 2 adjacent its outer edge. The outer ends of these lugs project inwardly beyond the inner face of the inner frame and are bent back upon the inner face thereof, as at 7, whereby the two frames are securely fastened 70 together.

The inner frame, which is straight or flat in cross-section, is also formed at suitable intervals with V-shaped teeth 8 which are struck up from the metal and are situated somewhat closer to the outer edge of the inner frame than the slots or openings 6, the purpose of which will presently appear.

It will be noted that the outer edge or margin of the outer frame 1 is formed with 80 an outwardly inclined inwardly projecting bead or rim 9 which separates the inner and outer frame sufficiently to accommodate the window pane and edge of the curtain material. As shown, the window pane is arranged in position between the inner and outer frames with its outer edge seating or bearing against the lugs 5 which hold the window pane against displacement or working out of place. The teeth of the inner frame penetrate or pass through the curtain material while the outer and inner edges of the two frames clamp the same and in this way, the outer and inner frames are securely fastened to the curtain. The inner edges of 90 the outer and inner frames also clamp the window pane and more securely hold the same in place. It will be noted, however, that while the teeth 8 pass through the curtain material, they do not penetrate the window pane as they are located beyond the outer margin of the latter.

By reason of the fact that the frame member 2 is provided with the openings 6 which receive the lugs 5 of the frame member 1, 105 and the teeth 8 which pass through the bead or rim 9 there is a double locking or securing connection between the frames 1 and 2 when the parts are assembled whereby the curtain and the pane of glass are securely 119 held in proper position with relation to each other.

From the foregoing description taken in connection with the drawings, it is thought that the construction, operation and advantages of my invention will be readily understood without requiring a more extended explanation.

Having described my invention, what I claim as new and desire to secure by Letters Patent, is:-

- 10 An automobile curtain window structure comprising an outer frame member provided with an inwardly disposed bead portion having openings and lugs, a second frame member having openings and teeth, the openings
15 of the first mentioned frame member adapted to receive the teeth of the second men-

tioned frame member and the openings of the second mentioned frame member adapted to receive the lugs of the first mentioned frame member, said bead portion spacing 20 the inner edge of the outer frame member from the adjacent surface of the second mentioned frame member, a window pane arranged between the two frame members with its edges adjacent the inner edge of the bead portion and a curtain fabric lying between the outer portions of the frame members and being penetrated by the lugs and teeth.

In testimony whereof I affix my signature.

WILLIAM M. CLONINGER.
